LOUIS MADDALENA, OF NEW YORK, N. Y.

CHICKEN-BROODER STOVE

Application filed May 1, 1929. Serial No. 359,505.

My invention relates to a brooder stove for breeding chicks and the like having an automatic heat control and oil feed.

Automatic brooder stoves have heretofore not found much favor with chicken breeders due to the fact that they fill the chicken coop or house with smoke and fumes, thus providing a very unhealthful atmosphere for the chicks and the like. The so-called automatic brooder stoves heretofore employed require a great deal of attention in order to provide the proper temperatures in the chicken house, they do not provide an even heat, are expensive to maintain and operate, and do not produce the beneficial results they should.

It is an object of my invention to provide a brooder stove for chicks and the like which will obviate all the disadvantages of the brooder stoves heretofore used.

Another object of the invention is to provide a brooder stove which will never discharge any smoke or fumes in the chicken house, will not produce any odors of any kind, and will be relatively inexpensive to maintain and operate.

A further object is to provide a brooder stove which will heat the chicken house and also create a warmer region around the stove for the chicks.

Still a further object is to provide a brooder stove which will be entirely automatic in its regulation of the temperature and supply of fuel to the stove burner, and which can be very easily dismantled or set up.

These and further objects and advantages will appear from a consideration of the following detailed description and accompanying drawings in which:

Fig. 1 is a vertical cross section, partly in elevation of the completely assembled brooder stove;

Fig. 2 is a front elevation of the lower portion of the brooder stove;

Fig. 3 is a horizontal section of the burner taken along the line III—III of Fig. 1; and

Fig. 4 is a front elevation partly in section of the oil supply tank from which the fuel oil is supplied to the burner.

Referring now to the accompanying drawings, 10 designates the burner comprising

standards or legs 11 supporting a circular base plate 12 provided with ridges 13 and a central opening 14.

As shown in Figures 1 and 3, ridges 13 support two open-ended cylinders 15 and 16, cylinder 15 being slightly longer than cylinder 16 and both being preferably made of sheet metal or the like. Ridges 13 also support four perforated blocks 17, preferably made of fire brick or similar substance, arranged concentrically around perforated cylindrical block 18 which is also made of fire brick or the like. Block 18 is provided with a central opening to correspond with opening 14 in the base plate 12, as is shown more clearly by Fig. 1. It will be evident that other means may also be employed for supporting in position cylinders 15 and 16 and blocks 17 and 18.

Supported on cylinder 15 and also on suitable supports 19 is an inverted frusto-conical cylinder 20 of sheet metal or the like provided with a lower flange 21 adapted to fit inside cylinder 15 as shown in Figure 1, and an upper flange 22. Above cylinder 20 is placed a frusto-conical cylinder 23 also of sheet metal or the like provided with a lower flange 24 which is adapted to fit around flange 22 on the outside thereof. Cylinder 23 is also provided with an upper flange 25 which supports a chimney 26 by fitting tightly inside the lower flange 27 of the chimney.

Securely fixed by suitable means in the upper end of cylinder 23 is a cross-bar 28 to which is secured the lower end of a bolt 29, to the upper end of which is slidably attached a damper 30 by means of nut 31 and expansion spring 32, the spring 32 being confined between cross-bar 28 and damper 30. By screwing the nut 31 up or down on the threaded upper end of bolt 29, a greater or less aperture is provided between the upper end of cylinder 23 and the damper 30, said upper end serving as a seat for damper 30. In this manner the draft on the burner 10 may be regulated very easily. A door 63 is provided in the chimney 26 above the damper so that access to the latter may be readily had.

Through cylinders 15 and 16 and resting on

the burner base plate 12 is pipe 62 which supplies fuel oil from the supply tank 33, said pipe 62 being provided with a valve 34 to enable the supply of fuel oil to be shut off when the brooder stove is not in operation.

Supply tank 33 rests on legs 80 and comprises a cup-shaped cylinder 64 of suitable material, in the upper end of which fits the neck 35 of fuel reservoir 36. Said neck 35 is provided with a well 37 in which any foreign matter or sediment in the oil will settle, and in which is located the filling opening normally closed by stopper 38. Said neck 35 is also formed with an opening 39, the upper end of which is formed into a valve seat. Very loosely supported in said opening 39 is valve rod 40 provided at its upper end with a valve 41 adapted to fit in said valve seat and seal same. The lower end of valve rod 40 when the supply tank 33 is assembled as shown in Figure 4, projects against the bottom of cylinder 64 and thus raises the valve 41 from its seat so that oil may flow through the opening 39 around valve rod 40 and into cylinder 64, from which it flows to the burner 10 through pipe 62. Around said valve 41 and its seat is preferably placed a filter 42 to prevent any sediment or foreign matter from flowing through pipe 62. A spring 43 is placed around rod 40 and bears against a projection on said rod and against the bottom of the neck 35 of the reservoir, as may be seen in Fig. 4.

Whenever the reservoir 36 is empty, it is lifted out of cylinder 64, righted and the stopper 38 removed, and the reservoir is then completely refilled with fuel oil. The stopper 38 is then reinserted and the reservoir inverted. When the reservoir is removed from cylinder 64, the spring 43 will act on valve rod 40 so as to seat the valve 41 and thus prevent any escape of oil.

After the reservoir has been thus inverted, it is again placed in cylinder 64, the neck 35 of the reservoir fitting in cylinder 64 so as to prevent any leakage, and the valve 41 will then be unseated by reason of the contact of the valve rod 40 with the bottom of cylinder 64, thus permitting a flow of fuel oil to the burner 10.

As will be readily understood, a little oil will flow by reason of gravity to the burner and collect on the base plate 12, and this oil may be ignited through the door 44 provided in the burner.

There will be no chance of the oil from the tank 33 overflowing the burner 10 because the pressure on the oil in the tank will be less than atmospheric.

In order to regulate automatically the temperature in the room and the flow of oil to the burner, the following construction is preferably employed.

Supported on cylinder 20 by means of Z

irons 45 or other suitable supports is an inverted frusto-conical cylinder 46 of sheet metal or the like and provided with a bottom but no top, the preferred shape of cylinder 46 and the manner in which it rests on cylinder 20 being clearly shown in Figure 1.

Cylinder 46 is provided at its upper end with a flange 47, inside of which fits lower flange 48 of frusto-conical cylinder 49 also of sheet metal or the like, the latter cylinder being provided with a top but with no bottom and its preferred form being illustrated clearly in Figure 1.

Secured to the bottom of cylinder 46 and passing therethrough is a pipe 50 which extends down through the central opening of cylindrical block 18 and opening 14 of the base plate 12 to below the burner. In this manner fresh air from the chicken house is passed directly to the chamber formed by cylinders 46 and 49 without any chance of it becoming contaminated with smoke or fumes from the burning fuel oil.

It will be noted that pipe 50 does not fill completely the central opening of block 18 nor the opening 14, and in this way a proper combustion of the fuel oil is assured, the necessary air passing around pipe 50 and through the perforations in the perforated block 18 and then through the perforations in the blocks 17.

Cylinder 49 is provided with an opening 51 surrounded by a flange 52, around which is fitted a sheet metal pipe 53 that projects through and above cylinder 23.

A bracket arm 54 is affixed to the pipe 53 and to its upper end 55 is pivotally secured a lever 56 which carries a slidably adjustable weight 57. Lever 56 carries at one of its ends a lid or cover 58 which is adapted to fit over the open top of pipe 53. Lever 56 is also pivotally connected at 59 with lever 60 which in turn is pivotally connected at 70 with lever 71. Lever 71 is connected to the operating member of valve 72 located in pipe 62, so that any raising or lowering of lid or cover 58 will close or open said valve 72 and thus regulate the flow of fuel oil through the pipe 62.

A frusto-conical umbrella or hover 73 is fitted around the upper end of cylinder 23 and extends outwardly and downwardly almost to the burner 10, a suitable opening being provided therein for the pipe 53.

The operation of the stove is as follows: when valve 34 is opened and the oil on the base plate 12 is ignited through door 44, the flames from the burning oil, illustrated by the solid line arrows in Figure 1, pass upwardly around the chamber formed by cylinders 46 and 49 and heat the air in said chamber. By reason of the overlapping of flange 47 of cylinder 46 on flange 48 of cylinder 49, no smoke or fumes will get into the chamber formed by cylinders 46 and 49. The flames also heat the air below the hover 73, some of

which escapes from under the hover to heat the entire chicken house. There will be, however, a warmer region directly under the hover, and in this region will congregate small chicks who have need of more warmth than the larger chickens. Cylinder 16 prevents any flames from heating cylinder 15 directly and thus there will be no chance of the checks burning themselves if they ever come in contact with cylinder 15.

The flames pass upwardly in the chamber formed between cylinders 46-49 and 20-23, and the smoke, gases and fumes therefrom escape through the chimney 26 which opens into the atmosphere above the roof of the chicken house.

It is a well known phenomenon of physics that heated air expands and due to this fact, the air in the chamber formed by cylinders 20 46 and 49 will raise the cover 58 from pipe 53 when the air in said chamber is heated sufficiently. The temperature at which this lifting of the cover 58 will take place can be controlled by moving the slideable weight 57 to the left or to the right, according to whether a higher or lower temperature in the chicken house is desired, the temperature in the chicken house varying with the temperature in the air chamber formed by cylinders 30 46 and 49. When the cover 58 is raised it decreases the supply of oil to the burner through levers 56, 60 and 71, as has been previously explained. The heated air escaping through pipe 53 also serves to heat the chicken house. 35 When the temperature in the said chamber and in the chicken house has fallen sufficiently, the cover 58, will drop on the pipe 53 and thus open wider the valve 72.

It has been found in practice that the 40 chicken brooder stove described above will maintain automatically a temperature of 90° F. under the hover and a temperature of 60° F. in the rest of the chicken house, practically ideal temperatures for the raising of 45 chicks and chickens.

It will be seen that I have provided a chicken brooder stove which is relatively inexpensive to construct, maintain and operate, which is practically automatic in its regulation 50 of the temperature under the hover and in the chicken house, is odorless and prevents any smoke or fumes from escaping into the chicken house, and which may be very easily set up and dismantled.

I do not wish to be limited to the specific 55 construction shown in the drawings as changes may be made therein without departing from the spirit of the invention. The drawings and description are to be considered as merely illustrative of the invention and not as limiting it, as the scope of the invention is to be ascertained by reference to the appended claims.

I claim:—

65 1. A chicken brooder stove comprising in

combination a burner, a fuel supply line for said burner, an air chamber above the burner, a second chamber surrounding said air chamber and communicating with the burner and the atmosphere so as to permit the escape of smoke and the like from the burner, and means operated by the expansion of the air in the air chamber to control the supply of fuel to the burner.

2. A chicken brooder stove comprising in 70 combination a burner, a fuel supply line for said burner, an air chamber above the burner, a second chamber surrounding said air chamber and communicating with the burner and the atmosphere so as to permit the escape of smoke and the like from the burner, and means for controlling the supply of fuel to the burner consisting of an outlet from said air chamber, a cover for sealing said outlet, a valve in said fuel supply line, and a system of levers connecting said valve with said cover so that movement of said cover will operate said valve.

3. A chicken brooder stove comprising in 75 combination a burner, a fuel supply line for said burner, a hollow cylinder above said burner and forming an air chamber, a second hollow cylinder above said burner and surrounding the first mentioned cylinder in spaced relation thereto, the second mentioned cylinder communicating with the burner and the atmosphere and thus permitting the escape of smoke and the like from the burner, and means operated by the expansion of the air in the first mentioned hollow cylinder to 80 control the supply of fuel to the burner.

4. A chicken brooder stove comprising in 85 combination a burner, a fuel supply line for said burner, a hollow cylinder above said burner and forming an air chamber, a second hollow cylinder above said burner and surrounding the first mentioned cylinder in spaced relation thereto, the second mentioned cylinder communicating with the burner and the atmosphere and thus permitting the escape of smoke and the like from the burner, a hover secured around the second mentioned cylinder and extending outwardly and downwardly almost to the burner, and means operated by the expansion of the air in the first mentioned cylinder to control the supply of 90 fuel to the burner.

5. A chicken brooder stove comprising in 105 combination a burner, a fuel supply line for said burner, a hollow cylinder above said burner and forming an air chamber, means for permitting the influx of fresh air to said cylinder, a second hollow cylinder above said burner and surrounding the first-mentioned cylinder but spaced therefrom so as to provide a chamber around the first chamber, the second cylinder communicating at the bottom thereof with the burner and at the top thereof with the atmosphere so as to permit the escape therethrough of the smoke and the 110

like from the burner, and means operated by the expansion of the air in the first-mentioned hollow cylinder to control the supply of fuel to the burner.

- 5 6. A chicken brooder stove comprising in combination a burner, a fuel supply line for the burner, an inverted frusto-conical cylinder above the burner having a bottom but no top, a frusto-conical cylinder having a top but no bottom above the first cylinder, its lower end fitting inside the upper end of the first cylinder and thus forming a chamber, an inverted frusto-conical cylinder communicating with the burner and surrounding the first-mentioned cylinder but spaced therefrom, a frusto-conical cylinder surrounding the second-mentioned cylinder but spaced therefrom, its lower end fitting around the upper end of the last mentioned cylinder and its upper end communicating with the atmosphere, means for permitting the influx of fresh air to the chamber formed by the two cylinders first mentioned, and means operated by the expansion of the air 25 in the said chamber to control the supply of fuel to the burner.

7. A chicken brooder stove comprising in combination a burner, a fuel supply line for the burner, an inverted frusto-conical cylinder above the burner having a bottom but no top, a frusto-conical cylinder having a top but no bottom above the first cylinder, its lower end fitting inside the upper end of the first cylinder and thus forming a chamber, 30 an inverted frusto-conical cylinder communicating with the burner and surrounding the first mentioned cylinder but spaced therefrom, a frusto-conical cylinder surrounding the second mentioned cylinder but spaced 35 therefrom, its lower end fitting around the upper end of the last mentioned cylinder and its upper end communicating with the atmosphere, means for permitting the influx of fresh air to the chamber formed by the two 40 cylinders first mentioned, and means operated by the expansion of the air in the said chamber to control the supply of fuel to the burner, consisting of an outlet for said chamber, a cover for sealing said outlet, a valve in the fuel supply line, and a system of levers connecting the valve with the cover so that movement of said cover will operate said 45 valve.

8. A chicken brooder stove comprising in combination a hollow cylinder forming an air chamber, means for permitting the influx of fresh air to said chamber, a second cylinder surrounding the first cylinder but spaced therefrom so as to provide a chamber around 50 the first chamber, the second cylinder having an opening in its bottom and communicating at its top with the atmosphere, a burner below said cylinders and communicating with the opening in the bottom of the second cylinder 55 and consisting of a base plate provided at its

center with an opening, a hollow cylindrical perforated fire block secured on the base plate around said opening therein, a series of perforated fire blocks secured on the base plate around the cylindrical fire block, a metal cylinder secured to the base plate and surrounding the series of fire blocks but spaced therefrom, a longer metal cylinder surrounding the last mentioned metal cylinder and spaced therefrom, the longer metal cylinder fitting 75 around the opening in the bottom of the second mentioned cylinder, a fuel supply line for furnishing fuel to the burner, and means operated by the expansion of the air in the said air chamber to control the supply of fuel to 80 the burner.
